ENGINE SPEED GOVERNOR

Marion Mallory, Detroit, Mich.

Application April 11, 1946, Serial No. 661,399

11 Claims. (Cl. 123—103)

1
This invention relates to speed control governors for internal combustion engines, and particularly to such governors of the vacuum actuated type.

The object of the invention is the provision of a novel and efficient governor of this type which is operable by intake manifold suction of the engine in conjunction with a centrifugally operated engine driven part, whereby a high vacuum condition in said manifold, as in the case of idling, will hold the governor throttle in full open position and means, responsive to a predetermined high speed running of the engine, will effect a release of the high vacuum condition and permit a closing or partial closing of the throttle under suction action in the manifold to reduce the fuel supply to the engine a predetermined extent.

The invention is fully described in the following specification, and a preferred embodiment thereof illustrated in the accompanying drawings, in which—

Fig. 1 is a fragmentary view of an engine, partly in section, embodying the invention; Fig. 2 is an enlarged fragmentary detail, partly in section, of the intake manifold of the engine, with the speed control throttle and suction device of the invention associated therewith, and Fig. 3 is an enlarged central longitudinal sectional detail of the centrifugal governor feature of the invention, with parts in full.

Referring to the drawings, 1 designates an internal combustion engine and 2 the fuel intake manifold thereto. In this manifold is located a throttle valve 3 of the customary butterfly type which may constitute the customary throttle valve of a carburetor interposed in said manifold or a separate throttle positioned in the manifold between the carburetor and the engine.

The throttle valve 3 is mounted on a shaft 4 crosswise of the manifold passage for rocking movements in such passage, and when in full closing relation to the passage is disposed in inclined position thereacross, as shown in dotted lines. This valve is preferably of the unbalanced type, having the outer wing thereof, or that which opens toward the engine, radially shorter than the other, thus requiring the axis of the shaft 4 to be offset from the longitudinal axis of the passage. This makes the valve more sensitive to a vacuum closing action in the manifold.

The valve shaft 4 has an arm 5 projecting from one end without the manifold 2, and the free end of this arm is connected by a rod 6 to

2
the diaphragm 7 in the chamber 8 of a suction device 9. The interior of this device at the side of the diaphragm 7 opposed to the arm 5 is the suction side of the device and has connection for such purpose through a line 10 and orifices 11 and 12 with the interior of the manifold adjacent to the throttle valve 3 with such orifices opening from the manifold passage at opposite sides of the valve 3 when in closed position.

10 While the device is operable by the use of the orifice 12 alone, it is preferable to provide both orifices in the arrangement shown.

The suction line 10 has a branch 13 communicating through a passage 14 in a centrifugal governor shaft 15 with a side passage 16 leading into a valve chamber 17 located in a rotatable head 18 attached to the shaft. A spring pressed valve 19 is mounted for radial movements in the chamber 17 and normally seats against the inner end of the chamber to close its communication with the passage 16. The valve spring 20 has its outer end thrust against a tension adjusting nut 21 in the outer end of the chamber and the valve 19 has grooves in its sides for the 25 passage of air from one end to the other of the chamber 17. The nut 21 has a relief opening 22 therethrough from the chamber 17.

The shaft 15, which is in suitable driving connection with the engine to cause it to be driven thereby, is journaled in a casing 23 and is provided at its outer end with a housing 24 that encloses the rotatable head 18 and provides a free space therearound into which the valve chamber opens through the opening 22 and has at one 35 side thereof a vent 25 to the atmosphere. It is thus apparent that when the head 18 is driven at a speed sufficient to cause an unseating of the valve 19 by centrifugal force, the vacuum in the suction device 9 and the passages communicating therewith is relieved, permitting the throttle valve 3 to be closed by action of the fuel thereon in its passage through the manifold 2. The communication between the passages 13 and 14 is through an annular recess 14' in the 40 shaft 15.

The throttle valve 3 is normally held open by the action of a spring 27 which is anchored at one end to the outer end of the arm 5 and at its other end to the manifold casing or other suitable stationary part. This spring is of weak tension so that it easily yields under a closing pressure on the valve 3. The opening movement of the valve 3 is limited by contact of an arm 30 on its shaft with a stop 31, preferably in the form of an adjusting screw that is threaded

through a stationary part 32 attached to the manifold casing.

The operation of the device is as follows: Assuming the engine to be idling, the vacuum through one or both orifices 11, 12, from the manifold passage 33 would be considerable, setting up a corresponding high vacuum in the line 10 and interior of the suction device 9. Relief of such vacuum is prevented by the seating of the valve 19 in the centrifugal device under the action of the spring 20. This high vacuum in the suction device 9 tends to hold the throttle valve 3 in its fully open position with the stop 30 tightly against the stop screw 31. There is likewise velocity passing by orifices 11 and 12, and so long as valve 19 is closed against its seat there will be suction in the suction device 9 sufficient to hold the valve 3 open. As the speed of the engine increases, the velocity and vacuum in the manifold intake passage tend to close the unbalanced valve 3 and, as soon as the speed increases to a point that the centrifugal force moves the relief valve 19 away from its seat in the chamber 17, the suction device 9 is relieved of its vacuum by opening of the passages 13, 14 and 16 to the atmosphere through the chamber 17 and bleed opening 25. This relieves the vacuum force, holding the throttle valve 3 open so that the only opening force acting on the valve is the light spring 27. In the event a load is applied to the engine that would cause the engine to slow down slightly, the valve 19 due to a slowing down of the rotating parts, will move inward to or toward seating position, thus stopping or reducing the bleed action and causing an increase of suction in the suction device 9 and a consequent movement of the throttle valve 3 to or toward a full open position. The desired maximum speed at which the engine is to be run can be obtained by adjusting the nut 21 to change the tension of the valve seating spring 20.

An important advantage of the present governor over those of a somewhat similar type heretofore used, so far as I am aware, is that should a leak occur in any of the vacuum passages, that is, passages 10, 13 or 14, or in the seat of the valve 19, or in the diaphragm 7, the governor valve 3 would close or move toward closed position and prevent the engine from running away.

It is apparent that I have provided an automatic engine speed governor that may be easily and quickly applied and set for any speed limit by an adjustment of the nut 21 controlling the tension of the relief valve spring 20; that it is responsive to vacuum in the fuel intake passage to maintain the throttle or governor valve in full open position, is responsive to engine speed to relieve such vacuum when a predetermined speed has been reached, and is also responsive to leaks in the vacuum system whereby a slowing down of the engine is effected when such condition is present and a destructive high speed running of the engine prevented.

I wish it understood that my invention is not limited to any specific construction, arrangement or form of the parts, as it is capable of numerous modifications and changes without departing from the spirit of the claims.

Having thus described my invention, what I claim as new and desire to secure by United States Letters Patent is:

1. A speed governor for internal combustion engines having, in combination with the engine fuel intake passage, a throttle valve movable to close said passage by suction action therein, a

vacuum device connected to said valve and having communication with said passage and responsive to suction action therein to hold said valve in open position, and means responsive to engine speed to relieve the vacuum in said device and permit closing of the valve when a substantially predetermined engine speed has been reached.

2. A speed governor for internal combustion engines having, in combination with the engine fuel intake passage, a throttle valve movable to close said passage by suction action therein, pneumatically operated means having connection with said valve and being in communication with and responsive to vacuum action in said passage to yieldingly hold said valve open, and means responsive to the engine speed to relieve the vacuum in said first means when the engine speed has been increased beyond a predetermined point.

3. A combination as called for in claim 2, wherein the speed responsive means includes a vacuum relief passage in communication with said means, and an outwardly opening normally seated valve in said relief passage induced by predetermined centrifugal force to open said passage.

4. A combination as called for in claim 2, wherein the speed responsive means includes an engine driven rotatable part having a radially disposed passage in communication at one end with the atmosphere and at its other end with the vacuum side of said first means, and a normally seated valve closing said radial passage and operable by predetermined centrifugal force upon rotation of said part to open said passage and relieve the vacuum force in said first means.

5. A combination as called for in claim 2, wherein the speed responsive means includes an engine driven rotatable part having a passage in communication at one end with the atmosphere and at its other end with the vacuum side of said first means, and a valve normally closing said passage and movable by centrifugal action to open said passage when a predetermined engine speed has been attained.

6. A speed governor for internal combustion engines having, in combination with the engine fuel intake means, a throttle valve operable to close under fuel feed suction action in said means and to normally stand in full open position, a vacuum responsive device connected to said valve and operable by vacuum action to hold the valve in open position, said device having communication with said intake adjacent to said valve whereby suction action in the intake means is communicated to said device, means forming a relief passage from said device and including a rotatable engine driven part, and a revoluble normally seated relief valve in said relief passage operable by centrifugal action upon rotation of said part to open said passage to relieve the vacuum action in said device and permit closing of the throttle valve when a predetermined engine speed is attained.

7. A speed governor for internal combustion engines having, in combination with the engine fuel intake means, a throttle valve operable to close under fuel feed suction action in said means and to normally stand in full open position, a vacuum responsive device connected to said valve and operable by vacuum action to hold the valve in open position, said device having its vacuum side in communication with said intake through a port at the inner side of said valve when closed

whereby suction action in the intake means is communicated to said device, means forming a relief passage from said device and including a rotatable engine driven part, and a normally seated relief valve in said relief passage operable by centrifugal action upon a rotation of said part at a predetermined speed to open said relief passage to relieve the vacuum action in said device and permit a closing of said throttle valve.

8. A combination as called for in claim 7 together with yielding means normally holding said relief valve seated and adjustable to vary its seating pressure.

9. A speed governor for internal combustion engines having, in combination with the engine fuel intake passage, a throttle valve movable by suction action in the passage to closed position therein, said throttle valve being of the butterfly type and unbalanced whereby suction action in the passage exerts a greater closing force than opening force on the valve, a vacuum device connected to said valve and having communication with said passage and responsive to suction action therein to hold said valve in open position, and means responsive to engine speed to relieve the vacuum in said device and permit closing of the valve when a predetermined engine speed has been attained.

10. A speed governor for internal combustion engines having, in combination with the engine fuel intake passage, a throttle valve movable to close the passage by suction action therein, an adjustable stop for the opening movement of said

valve, spring means exerting a weak tension on the valve to normally retain it in open position, a vacuum device connected to the valve and having communication with said passage and responsive to suction action therein to hold the valve in full open position, and means responsive to engine speed to relieve the vacuum in said device and permit closing of the valve when more than a predetermined engine speed has been attained.

11. A speed governor for internal combustion engines having, in combination with the engine fuel intake passage, a throttle valve movable to close said position by suction action therein, a vacuum device connected to said valve and having communication with said passage and responsive to suction action therein to hold said valve in open position, said valve being responsive to suction action in said intake passage to move it to closed position upon reduction in vacuum in said device by leakage or otherwise, and means responsive to a predetermined engine speed to effect a relatively sudden release of such vacuum.
